CLAIM

The ornamental design for a turbo pressure chamber, as shown and described.

DESCRIPTION

FIG. 1 is a front, top, and right side perspective view of a turbo pressure chamber showing my new design. The broken line shows an exhaust is for illustrative purposes only and forms no part of the claimed design;

FIG. 2 is a rear elevation view thereof;

FIG. 3 is a front elevation view thereof;

FIG. 4 is a top plan view thereof;

FIG. 5 is a bottom elevation view thereof;

FIG. 6 is a left side elevation view thereof; and,

FIG. 7 is a right plan view thereof.

FIG. 1

FIG. 2

FIG. 3

FIG. 4

FIG. 5

FIG. 6

FIG. 7
